[57] CLAIM

The ornamental design for a remote cable connector or
similar article, as shown and described.

DESCRIPTION

FIG. 1 is an upper right side perspective view of a
remote cable connector or similar article showing our
new design. The broken line showing is included for the
purpose of illustrating environmental elements only and
forms no part of the claimed design;

FIG. 2 is a left side elevational view thereof, the right
side elevational view thereof being a mirror image;

FIG. 3 is a top plan view thereof, the bottom plan view
thereof being a mirror image;

FIG. 4 is a rear end elevational view thereof.

FIG. 1

FIG. 3

FIG. 4

FIG. 2
